UNITED STATES PATENT OFFICE.

LABAN W. NEEDHAM, OF CHICAGO, ILLINOIS.

ENGINE-STARTER.

1,147,424.

Specification of Letters Patent. Patented July 20, 1915.

Application filed November 23, 1914. Serial No. 873,475.

To all whom it may concern:

Be it known that I, LABAN W. NEEDHAM, a citizen of the United States of America, and a resident of Chicago, in the county of Cook, State of Illinois, have invented certain new and useful Improvements in Engine-Starters, of which the following is a specification.

This invention relates to the manually actuated type of starters for automobile and like engines, and more particularly to the type of such starters which are actuated from the seat of an automobile.

And the present improvement has for its object to provide a simple and efficient structural formation and association of parts, adapted to afford a substantial operative engagement between the actuating mechanism and the actuated drum of the engine shaft, and in which an automatic and immediate relief of such operative engagement is effected by the forward rotation of the engine shaft under the influence of the engine piston. The arrangement being such that with the actuating mechanism in its inactive position frictional contact with the drum of the engine shaft is prevented, with a consequent avoidance of noise and wear of parts during the ordinary running of the engine, all as will hereinafter more fully appear.

In the accompanying drawings:—Figure 1, is a perspective view showing the general arrangement of the present starter mechanism as applied to an automobile. Figs. 2 and 3, are companion detail elevations of the starter mechanism, showing the same in an inactive position and in an active position, respectively.

Similar reference numerals indicate like parts in the several views.

Referring to the drawings, 1 represents the internal combustion engine of an automobile, having the usual engine shaft 2, with which the present starter mechanism is associated. Said engine being mounted on the forward portion of the under-frame 3 of the automobile.

4 designates a drum fixedly secured to the engine shaft 2 and having a cylindrical perimeter adapted for frictional engagement with the hereinafter described clutch band of the starter mechanism.

5 designates the clutch band above referred to, and which is arranged to encircle the drum 4 aforesaid. Said clutch band 5

is formed of a strip of metal bent into a hoop shape and formed with means for attaching the respective ends thereof to the floating lever hereinafter described. In the construction shown in the drawings, the above mentioned attaching means comprises an eye 6 at one end of the band, and an angularly disposed flange 7 at the other end.

8 designates the floating lever above referred to, and formed at one end with a lug or shoulder 9 for engagement with the aforesaid attaching flange 7 of the clutch band 5. In spaced relation to said lug or shoulder 9, the lever 8 carries a cross pin 10, adapted for engagement with the attaching eye 6 of the clutch band 5.

11 designates one or more springs attached at one end to the automobile frame 3, and at the other end to the lever 8, adjacent to the aforesaid cross-pin 10, and adapted to draw said floating lever 8 and its associated clutch band 5 into the normal inactive position illustrated in Fig. 2.

12 designates a fixed rest or abutment against which the floating lever 8 is drawn by the springs 11, in a return of said mechanism to an inactive position. And in such movement as the floating lever 8, attains a position of rest upon the abutment 12, the inner end of said lever is canted into a position wherein the attaching ends of the clutch band 5 are spread apart and the diameter of the main hoop shape portion of said band increased, so that it will be entirely free from contact with the perimeter of the aforesaid drum 4. Under such conditions said drum 4, is free to rotate without friction or noise arising from contact between the described parts.

13 designates a chain or like flexible operating connection extending from a point adjacent to the front seat of the automobile, and having next to said seat an operating handle 14. Intermediate of its length said flexible connection is deflected around a guide pulley or sheave 15, and at the other end to that above mentioned is operatively connected to the aforesaid floating lever 8, preferably by the intermediate link now to be described.

16 designates an angularly disposed link or bar pivoted to the outer end of the lever 8, aforesaid, and held in such angular relation by a stop shoulder 17. With such construction the initial movement of the float-

ing lever 8, is effected with the link 16, in its angular position, and supported therein by the shoulder 17. As said lever 8 advances in its active movement, the link 16, leaves 5 said shoulder 17, and its further function is the same as a link or section of the aforesaid flexible connection 13, to which it is connected.

18 designates a pair of transversely ar-
10 ranged rails secured to the automobile frame
3, and disposed in spaced relation so as to
receive between them the floating lever 8,
and act as a guide for the same in the final
15 portion of its active movement, and during
a corresponding portion of its return move-
ment.

The general operation of the starting
mechanism is substantially the same as the
friction band starting mechanism, hereto-
20 fore used or proposed, and briefly stated is
as follows:—With an initial movement of
the floating lever 8, the attaching ends of the
clutch band 5 are drawn together with relation
25 to the hoop shaped main portion of the
clutch band, with a corresponding diminu-
tion in the diameter of said hoop shape
portion. Accordingly said hoop shaped portion
30 is caused to firmly grip and engage the
perimeter of the drum 4 of the engine shaft,
so that further active movement of the lever
8, will effect a circular movement of both the
clutch band 5 and drum 4, and attain the de-
35 sired compression of a charge of fuel in the
explosion chamber of the engine.

Having thus fully described my said in-
vention what I claim as new and desire to
secure by Letters Patent, is:—

1. In a starter for internal combustion en-
gines, the combination with a drum fixed on
40 the engine shaft, of a clutch band encircling
said drum, a floating lever having attach-
ment at its inner end with the respective
ends of the clutch band, a spring for return-
ing said lever to its inactive position, and a
45 stationary abutment adapted to support said
lever in an inactive position and insure a
movement of the inner end of the same to
cause a spreading of the clutch band and
free the same from contact with the drum

aforesaid when the starter mechanism is in- 50
active, substantially as set forth.

2. In a starter for internal combustion en-
gines, the combination with a drum fixed on
the engine shaft, of a clutch band encircling
55 said drum, a floating lever having attach-
ment at its inner end with the respective
ends of the clutch band, a spring for return-
ing said lever to its inactive position, a sta-
tionary abutment adapted to support said 60
lever in an inactive position and insure a
movement of the inner end of the same to
cause a spreading of the clutch band and
free the same from contact with the drum
aforesaid when the starter mechanism is in- 65
active, a flexible pull connection associated
with said floating lever and extending to a
point adjacent to the seat of the operator,
and a sheave for deflecting said connection
intermediate its length, substantially as set 70
forth.

3. In a starter for internal combustion en-
gines, the combination with a drum fixed on
the engine shaft, of a clutch band encircling
75 said drum, a floating lever having attach-
ment at its inner end with the respective
ends of the clutch band, a spring for return-
ing said lever to its inactive position, a sta-
tionary abutment adapted to support said 80
lever in an inactive position and insure a
movement of the inner end of the same to
cause a spreading of the clutch band and
free the same from contact with the drum
aforesaid when the starter mechanism is in- 85
active, an angularly disposed link pivoted at
the outer end of the floating lever, said lever
having a lateral abutment for said link, a
flexible pull connection attached to said link
and extending to a point adjacent to the seat 90
of the operator, and a sheave for deflecting
said connection intermediate its length, sub-
stantially as set forth.

Signed at Chicago, Illinois, this 21st day
of November, 1914.

LABAN W. NEEDHAM.
